UNITED STATES PATENT OFFICE.

RAGNAR WIKANDER, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTROMAGNET.

1,199,447.

Specification of Letters Patent. Patented Sept. 26, 1916.

Application filed March 23, 1911. Serial No. 616,478.

To all whom it may concern:

Be it known that I, RAGNAR WIKANDER, a subject of the King of Sweden, and a resident of Pittsburgh, in the county of Allegheny and State of Pennsylvania, have invented a new and useful Improvement in Electromagnets, of which the following is a specification.

My invention relates to switches for electric circuits and it has special reference to such switches as are electrically operated and are adapted for use in unit switch control systems.

The object of my invention is to provide a switch of the character above indicated that shall be simple and durable in construction, easily adjusted and adapted to provide various operating characteristics and for use under varying conditions of service.

20 In my co-pending application, Serial No. 616,479, filed of even date herewith, I have shown and described a switch operated by an electro-magnet possessing the operating characteristic of actuating the switch only 25 when energized within predetermined limits. According to my present invention, I provide a switch having the same characteristics in general but possessing a number of important features not found elsewhere, as 30 follows:

The adjacent pole pieces of the stationary and movable core member, which are brought into engagement with each other when the switch is closed, are provided with 35 flanges or enlargements of magnetizable material, which materially influence the distribution of flux in the members when the air gap between them is considerable, but which are spaced slightly from the ends of 40 the opposed faces so that they do not come into engagement with each other and so that they have no appreciable influence when the switch is closed and the air gap is of least width.

45 In addition to the foregoing, the core structure comprises an auxiliary core member which is adjustable relative to the main stationary member and is provided with an independent coil which may advantageously 50 be connected in series relation to the electric motor when the switch constitutes a part of a unit switch controller.

Figure 1 of the accompanying drawings is a side elevation, certain of the parts being 55 broken away and shown in section, and Fig.

2 is a front elevation of a switch embodying my invention. Figs. 3, 4, 5, and 6 are detail views of the structure of Figs. 1 and 2, and Fig. 7 is a view corresponding to Fig. 1 of a modified switch structure embodying my invention.

Referring to the drawings, the switch here shown comprises a supporting rod or bar 1 having an insulating jacket 2, a contact post 3 to which stationary contact member 4 is secured. A stationary U-shaped core member 5, an auxiliary L-shaped core member 6, movable core members 7 and 8 constituting the armature of the magnet and a movable contact member 9 which co-operates with the stationary contact member 4.

The stationary members 3 and 5 are rigidly secured to the insulated rod 1, the L-shaped member 6 is adjustably secured thereto and the movable core members 7 and 8 are pivotally supported upon stationary side brackets 10 which are mounted thereon.

A magnetizing coil 11 is mounted upon one arm of the U-shaped member 5, the other arm 12 of which is removably secured to side brackets 10 by means of screws 13. A coil 14 may be mounted on the outwardly extending arm of the L-shaped member 6, as shown in Figs. 1 and 2, or omitted as shown in Fig. 7. The coil 14, or, if it is omitted, the magnetizing coil 11, is preferably energized in accordance with the current supplied to the motor, in the control of which the switch is utilized.

The member 6 is supported by a bracket 15 which is bent around the insulated rod or bar 1, as shown in Fig. 1 of the drawings, and adjustment is effected by means of a screw 16 which is screwed into a projection 17 of the bracket 15 and is rotatably supported by means of a block 18, said block being clamped to the insulated rod 1, directly below the L-shaped member 6, by means of bolts 19 and a clamping member 20. The arm of the core member 5, on which the coil 11 is mounted, is provided, near its outer end, with lateral projections or flanges 21 of magnetizable material, the outer surfaces of which are substantially parallel to the pole face, but the body of the core member extends slightly beyond the surface of the flanges.

The movable core member 8 is divided into two parts located at the respective sides of the movable core member 7 and pivotally

mounted on a shaft 22. The upper ends of the core member parts 8 are provided with laterally extending magnetizable projections 23 which are similar to the projections 21 5 and are correspondingly located but are spaced slightly from the pole faces of the members 8 which come into engagement with the upper arm of the member 5.

Strips 24 are secured to the inner adjacent 10 surfaces of the members 8 and extend downwardly and constitute L-shaped supports 25. A spacing block 26 is pivotally mounted between the members 25 and is provided with a tapped hole 27 to receive a screw-threaded 15 rod 28.

The movable member 7 which, as above indicated, is pivoted on the shaft 22 and is located between the members 8, extends from the upper arm of the member 5 downwardly to a point opposite the outwardly 20 extending arm of the member 6 and is provided with side plates 29 which extend beyond its upper end and support the movable contact member 9. The side plates 29 are 25 also provided with outwardly extending projections 30 which pivotally support guide blocks 31 and 32. The rod 28 extends loosely through a hole in the block 31 and is provided with a collar or enlargement 31^a. A 30 spring 43 surrounds the rod and is interposed between the collar 31^a and block 31.

A rod 33, which is similar to the rod 28, is pivotally secured, by means of a pin 34, to contact member 9 and extends loosely 35 through a hole 35 in the guide block 32. A spring 36 surrounds the rod 33 and tends to produce a rotary movement of the contact member 9 about its pivot 37, within limits which are determined by an enlargement 38 40 on the lower end of the rod 33. The side brackets 10 are secured to the insulated rod 1 and are electrically connected, by means of bolts 40, to a stud 39 which constitutes one terminal of the switch. Flexible shunts 45 41 complete an electrical connection between the stud 39 and the contact member 9, since they are fastened to the outer ends of the side brackets 10 and to ledges 42 of the contact member.

50 The spring 43 is normally held in compression between the collar 31^a and the block 31 and has no effect upon the action of the armature of the magnet as a whole but is further compressed by, and opposes a relative 55 movement between, the parts 7 and 8 of the armature as indicated hereinafter. It is therefore evident that, when both magnet coils are deenergized, the action of gravity will open the switch and hold the 60 lower end of the core member 7 in engagement with the pole face of the L-shaped core member 6.

The operation of the switch is as follows: If it is assumed that the switch occupies 65 its open position, the coils 11 and 14 being

deenergized and the lower end of the core member 7 being in engagement with the pole face of the L-shaped core member 6; the switch will be closed if the coil 11 alone is energized or if the coil 14 is supplied with a 70 relatively small current. Under these conditions, the core members 7 and 8 will both be attracted by the upper arm of the core member 5 and will act together. If the coil 14 is omitted and the arm 12 of the core 75 member 5 is materially less in cross section than the upper arm as shown in Fig. 7, the switch will be held open provided the coil 11 is energized above a predetermined value, since the flux produced in the core member 80 5 will quickly saturate the arm 12, thereby forcing considerable leakage flux through the L-shaped member 6 and the core member 7. Under these conditions the core members will not act together, but the core member 85 7 will be held in engagement with the core member 6, while the core member 8 will be moved into engagement with the upper arm of the core member 5. The position of the core member 7, however, determines the position of the switch, since the contact member 9 is carried at its upper end, and the independent movement of the core member 8 will tend only to compress a spring 43 which surrounds the rod 28. As the current in the coil 11 is diminished, the leakage flux passing through the member 7 will be very rapidly diminished until the spring 43 will overcome the attraction between the members 6 and 7 and will close the switch. 100

If a series of switches of the character above described are so arranged that their coils 11 are successively energized, and if the arm 12 of the core member 5 is substantially equal, in cross section, to the remainder of the core, substantially the same action may be produced by utilizing the coil 14 and making its current dependent upon the current supplied to a motor or other device controlled by the switches. Under 105 these conditions, when the coil 14 is energized above a predetermined amount, the core member 7 will be held in engagement with the member 6 and the switch will be held open until the current in the coil 14 110 falls below a predetermined value. The values at which the switch will be closed may be varied by varying the number of turns of which the coils are composed or by adjusting the air gap at 44 between the 115 members 5 and 6.

The lateral projections 21 and 23 of the core members 5 and 8 serve to distribute the flux over a wide area when the members are separated by a material air gap, such 120 as that which exists when the switch is open, since they are nearly flush with the main pole faces of the core members with which they are associated, but, inasmuch as they are separated by an air gap when the main 125 130

5 pole faces are in engagement, they have practically no effect on the distribution of flux under the last named conditions. The projections are particularly valuable for this reason since they permit a very strong 10 pull, the flux being concentrated in the main pole faces when they are in contact, tending to hold the members in engagement when the switch is closed, but enable the switch to be more readily held open, either 15 by the action of the coil 14 or by the leakage flux traversing the core member 6.

My invention is not restricted to the structural details illustrated, and is only limited 15 by the appended claims. The switch may be utilized for various purposes within the spirit and scope of the invention.

I claim as my invention:

1. An electromagnet comprising a pair of 20 core members having an air gap between them, one of said members constituting a shunt magnetic path for the other, an armature member, and means for adjusting one of said core members to vary the length of 25 said air gap and to vary the distance between said core member and said armature member.

2. An electro-magnet comprising a stationary U-shaped core member, a normally 30 stationary, but adjustable, L-shaped core member coöperating with said U-shaped core member, and a movable armature member that is pivotally mounted at the outer 35 end of one of the arms of the U-shaped core member and coöperates with both stationary members.

3. An electro-magnet comprising a stationary core member having a flange or enlargement parallel to but slightly spaced 40 from, one of its pole faces, and a coöperating movable core member having a corresponding enlargement.

4. An electromagnet comprising relatively 45 movable magnetizable members between

which a normal distribution of flux occurs 45 when they are in engagement and means on said members for materially influencing the distribution of flux when they are separated from each other.

5. An electro-magnet comprising a stationary U-shaped core member, a normally 50 stationary, but adjustable, L-shaped core member adjacent to said U-shaped core member and coöperating therewith, and a movable armature member that coöperates 55 with both stationary members.

6. An electro-magnet comprising a stationary U-shaped core member, a normally 60 stationary, but adjustable, L-shaped core member coöperating with said U-shaped core member, a compound movable core member one part of which coöperates with the stationary members and a second part of which is yieldingly connected to the first part to coöperate only with the U-shaped member. 65

7. An electromagnet comprising a relatively stationary core member, an auxiliary core member for providing a shunt magnetic path, and a movable member coöperating 70 with both core members, said auxiliary core member being adjustable to vary the reluctance of said shunt magnetic path.

8. An electromagnet comprising a pair of relatively movable core members, one of 75 which constitutes a shunt magnetic path for the other, a member coöperating with said core members, and means for adjusting one of said core members to simultaneously vary the distances between it and the other core member and the coöperating member. 80

In testimony whereof, I have hereunto subscribed my name this 21st day of March, 1911.

RAGNAR WIKANDER.
